Edward C. Sasnett

Attorney

UNITED STATES PATENT OFFICE.

HARRY REX MCKELLAR, OF SAN FRANCISCO, CALIFORNIA.

KEY.

Application filed March 3, 1927. Serial No. 172,388.

This invention relates to keys for locks, and particularly to devices for identifying keys as to their ownership, use and the like.

It is a matter of common experience that 5 keys are frequently lost and rarely recovered, causing great inconvenience and loss of time in having new locks fitted or duplicate keys, which are often unsatisfactory, made by a locksmith. It is believed that if a lost key 10 should be plainly marked with the name and address of the owner, and perhaps with an offer of reward for its return, the chance of restoration to its owner would be very good indeed. Where keys are aggregated 15 in a bunch, it is oftentimes troublesome to find the particular key wanted, especially where the bunch of keys are used by several persons, or where a particular key is sought for in the dark. It is an object 20 of this invention therefore to provide a device for marking keys that is easy and convenient to apply, does not detract from the strength or appearance of the key, that is flexible so as to provide for change of owner- 25 ship or use of the key, and that may be rendered visible in darkness. The particular construction and advantages of devices embodying the invention will be readily understood from the following detailed de- 30 scription in which reference is made to the accompanying drawings, whereof:

Fig. 1 is a plan view of a key, such as used with an ordinary lock, having applied thereto marking devices constructed in accordance 35 with my invention;

Fig. 2 is a sectional view taken on line 2-2 of Fig. 1;

Fig. 3 is a detail view showing a retaining slide for the letter blocks having a slightly 40 different form from that of the slide shown in Fig. 1;

Fig. 4 illustrates a form of marking device suitable for smaller keys;

Fig. 5 is a sectional view corresponding 45 to Fig. 2, but showing a modified form of locking slide; and

Figs. 6, 7 and 8 illustrate three different forms of locking element for the slide.

Referring to these drawings, and particu- 50 larly to Figs. 1 and 2, the circular handle of the key is formed on one face near the periphery with a shallow circular slot 10, which extends from the point *a* to the point *b*, where it opens into a relatively wide slot 11 cut entirely through the thickness of the key handle and extending diametrically

from the periphery to a point inwardly beyond the center of the handle.

Letter blocks 12 are adapted to be inserted into the circular slot 10 at the open end *b* 60 thereof. These blocks may be of metal or may be formed of a suitable composition. It will be observed from Fig. 2 that the slot 10 is wider at the bottom than at the top; that is this slot is preferably slightly 65 dove-tail in cross section. The sides of the letter blocks 12 are correspondingly beveled and curved, so that they have a nice sliding fit in groove 10, the thickness of the blocks being such that when the blocks are inserted 70 their top faces are flush with the face of the key handle. These blocks may, for example, be arranged to spell the name and address of the owner, suitable plain spacing blocks 12' being provided for separating the words 75 or filling gaps in the lettering, and a plain block 12'' being placed at the open end of the slot to coact with the locking slide 13. The walls and inner end of slot 11 may be convex in cross section, as shown in Fig. 2, 80 and the sides of the locking slide 13 will of course be concave so as to have a nice sliding fit with the walls of the slot. This slide is inserted after the letter blocks have been arranged in slot 10 and after the insertion of 85 terminal block 12''. In case slot 11 is cut entirely through the key handle, as shown, the thickness of the slide is made equal to the thickness of the key handle, so as not to weaken the key and preserve the usual appearance thereof, the length of the slide being 90 such that when the slide is fully inserted its curved outer edge will form a continuation of the circular periphery of the key handle.

Slide 13 is formed with a semicircular 95 notch 14 which registers with a semicircular notch in the handle and therewith forms a circular hole partly through the handle and partly through the slide. A split key ring 15 may be passed through this hole 100 and will then lock the slide against displacement, the slide in turn retaining the letter blocks. Obviously any convenient number of keys equipped with the identification devices described may be strung on 105 the ring 15, or one key thus marked may serve as a key tag for a bunch of keys.

The slide may be formed with a shallow slot 16 similar in cross section to the circular slot 10, and extending from the inner 110 end of the slide to a point *c* short of the outer end. Letter blocks 17 of rectangular

form may be inserted in slot 16 from the open end thereof prior to insertion of the slide, these blocks spelling a word or words indicating, for example, the use or function of the key. Blocks bearing figures may be furnished for indicating the numbers of houses, streets, rooms, etc., and bearing any other devices or symbols for which there is a demand.

10 The letter blocks may be of any convenient or desired size, within the limits imposed by the size of the particular key to which they are applied. A plurality of rows of letters may be used. Fig. 3, for instance, 15 shows a slide 13' formed with two grooves adapted to seat two rows of letters. The slide itself may be made up of separate blocks bearing suitable indicia. The letters may be formed so as to be readable in the 20 dark or by blind persons. For the use of the blind, the letters will be raised or embossed. For rendering the letters visible in the dark they should be made sufficiently large, depressed, and coated with so-called 25 aluminum paint. Permanent information, such as the city and State of the owner, may be stamped on the key by the retailer, while the manufacturer may stamp such legends as, Reward for return.

30 Fig. 4 shows a small key furnished with a slide 18, but without the circular series of lettering shown in Fig. 1, the diameter of the handle in this case being too small to accommodate the circular series. The 35 slide 18 may bear on one or both faces any desired indicia which may be formed, for example, by the simple means of nail and hammer, or with a center punch. In this modification the slide is locked by a relatively 40 small split ring 19, which may also serve as attaching means to a larger key ring. Larger keys may of course be provided with a slide such as 18 associated or not with a circular series of letters in the 45 handle.

50 Fig. 5 shows a slide 13' of different form from that shown in Fig. 2. In this modification the sides of the slide and also the inner end are convex in cross section while the walls of its slot 11' are concave. This 55 form adapts the slide to be formed of two or more complementary pieces. As shown, the slide is formed of two identical superposed halves, the concave form of the slot walls holding the parts together. A slide of this construction is adapted to contain secret inscriptions on the inner hidden faces of the two halves, such inscriptions containing information for the owner's use 60 only, for example, information relative to a depository, such as a safety deposit box, to which the key belongs; or the finger print of the owner may be preserved between the inner faces of a slide of this construction. 65 Of course this modified form of slide is also

adapted to bear letter blocks on its outer faces.

Instead of locking the slide with an ordinary key ring, as shown in Fig. 1, or with a small split ring as shown in Fig. 4, various other forms of locking elements may be employed within the scope of the invention. Figs. 6, 7 and 8 for example, show three different forms of locking element. That shown in Fig. 6 consists of a D-shaped 75 piece of tubular metal having the member 20 integrally joined to member 21, but separate from and abutting member 22. The metal is resilient so that this element may be applied by forcing part 22 away from part 20 with a pair of pliers sufficiently to pass the key handle between these parts to bring the part 20 into registry with the hole partly in the handle and partly in the slide, whereupon the parts are released and part 20 snaps through the hole, locking the slide.

The locking element shown by Fig. 7 consists of a U-shaped piece of metal 23 joined near the ends by a screw 24. This screw is round and approximately of the same diameter as that of the hole in the slide and key handle, and the lock is applied by inserting the screw through said hole and screwing it home. Fig. 8 shows a locking element of D-shape having a split portion at 25 through which the key handle is adapted to be inserted and the split end passed through the hole, the portion 26 of this element being approximately of the same diameter as the hole and adapted to be snugly received thereby.

Now having particularly described devices embodying my invention, what I claim as new and desire to secure by Letters Patent of the United States is:

1. In combination with a key having a handle formed with a slot, a slide in said slot bearing suitable indicia, said slide and handle being formed with registering semi-circular recesses, and a locking element in the hole defined by said recesses.

2. In combination with a key having a circular handle formed with a diametrically extending slot having its side walls curved in cross section, a slide bearing suitable indicia fitting said slot, said handle and slide having registering notches forming an aperture, and a locking element passing through said aperture.

3. In combination with a key having a circular handle formed with a shallow circular slot adjacent its periphery and formed with a diametrical slot into which one end of said circular slot opens, letter blocks fitting said circular slot, a slide in said diametrical slot, and means for locking said slide.

4. In combination with a key having a circular handle formed with a shallow circular slot adjacent its periphery and formed

with a diametrical slot cut entirely through the thickness of the handle, said circular slot opening at one end into said diametrical slot, said circular slot being dove-tail in cross section and said diametrical slot having side walls curved in cross section, letter blocks fitting said circular slot, a slide fitting said diametrical slot, said slide and handle being formed with complementary notches forming a circular aperture, and a split key ring passed through said aperture.

5. In combination with a key having a handle formed with a slot open at one end, a

slide bearing suitable indicia adapted to be inserted through the open end of said slot, 15 said slide having a semicircular notch in one edge and said handle formed with a complementary notch adapted to register with said semicircular notch when said slide is fully inserted to form a hole partly in the 20 slide and partly in the handle, and a locking element passing through said hole.

In testimony whereof I hereunto affix my signature.

HARRY REX. MCKELLAR.
